UNITED STATES PATENT OFFICE.

BURTON L. JOHNSON, OF KNOXVILLE, TENNESSEE.

DISPLAY-CABINET.

1,379,867.

Specification of Letters Patent. Patented May 31, 1921.

Application filed March 11, 1919. Serial No. 281,973.

To all whom it may concern:

Be it known that I, BURTON L. JOHNSON, a citizen of the United States, residing at Knoxville, in the county of Knox and State 5 of Tennessee, have invented a new and useful Improvement in Display-Cabinets, of which the following is a specification, reference being had to the accompanying drawing.

10 My improvement relates particularly to structures used for displaying articles of merchandise, for example, candies. The object of the invention is to provide such a structure adapted to display at the same time a considerable number of samples of candies, portions of said samples being accessible and others being visible but inaccessible and excluded from the atmosphere.

In the accompanying drawings,

20 Fig. 1 is a front elevation of a structure embodying my improvement;

Fig. 2 is an upright section on the line, 2—2, of Fig. 1, looking toward the left;

25 Fig. 3 is an upright detail section showing one of the drawers and walls forming a compartment for the drawer;

Fig. 4 is an upright section on the line, 4—4, of Fig. 3, looking toward the right;

30 Fig. 5 is a longitudinal upright section through the front or outer part of one of the drawers;

Fig. 6 is a perspective view of a box-like container, the two parts being separated from each other.

35 Referring to said drawings, A is a base or floor; A¹ is a back wall; A², A², are upright end walls; A³ is a horizontal top wall; A⁴, A⁴ are upright partitions extending from the front rearward as far as the drawers are to

40 extend; A⁵, A⁵, are horizontal partitions extending rearward as far as the drawers are to extend. A stop bar, A⁶, extends horizontally across the rear end of each upright partition, A⁴, between the partitions, A⁵, to

45 form a stop or limit for the rearward movement of the drawers. The front edges of the end walls and the partitions, A⁴, are inclined rearward. That makes the front of the structure slant rearward. The rear edges 50 of the partitions, A⁴, slant rearward in a plane which is parallel with the plane of the front of the structure.

55 The base or floor, A, and the top wall, A³, and the end walls, A², and the partitions, A⁴ and A⁵, form horizontal compartments which receive drawers, B. The ends of said

compartments are inclined rearward because the partitions, A⁴, have their front and rear edges inclined as above described.

The forward or outer ends and the rear 60 or inner ends of the drawers are inclined so as to conform to the slant of the ends of said compartments. The rear or inner ends of the drawers bear against the stop bars, A⁶.

Every drawer has in the front of its outer 65 end wall a chamber or recess, B¹, in which rests a container, C, formed of sheet metal. The faces of said chamber which meet the outer faces of the drawer are perpendicular to the end of the drawer. On account of the 70 slant of the end of the drawer, this brings the upper and the lower of said faces oblique to the length of the drawer.

Said container is in box form and comprises a body, C¹, and a lid, C², having side 75 wings, C³, adapted to extend over the side walls, C⁴, of the body, C¹. The wings, C³, are to be bent outward far enough to cause their free edges to bear against the inner faces of the chamber, B¹, and make such 80 frictional engagement in said chamber as will hold said lid in said chamber. The depth of said chamber and the corresponding dimension of the container are preferably equal so as to bring the outer face of 85 the container flush with the outer face of the end of the drawer.

In the lid of the container is a window opening, C⁵. On the inner face of the lid, a plate of glass, C⁶ extends over said opening 90 and is held in position by retaining members, C⁷, seated on the inner face of the lid and extending over the edge of the plate, C⁶.

An aperture, B², extends from the chamber, B¹, rearward through the outer end 95 wall of the drawer. A finger or other object may be extended through said aperture from within the drawer to bear against the container, C, and force the container out of the chamber, B¹. A knob, B³, seated on the 100 outer end wall of the drawer is to be engaged to pull the drawer outward.

Immediately at the rear of the place occupied by the front wall of the drawer when the drawer is closed, a stop member, A⁷, is 105 secured to the lower face of the adjacent superposed partition, A⁵, or, in the case of the upper compartments, top wall, A³. When the drawer is pulled outward horizontally, the inner end wall of the drawer 110 meets said stop member. This engagement prevents pulling the drawer forward hori-

zontally so far as to release it and let it fall. But the drawer may be entirely removed from its compartment by pulling it outward until its rear end wall engages or nearly 5 engages the stop member, A⁷, and then lifting the outer end of the drawer, whereby the rear end wall is lowered sufficiently to pass outward beneath the stop member, A⁷. For inserting the drawer, a reverse movement is 10 made, the outer end of the drawer being raised and the drawer then moved rearward until the inner end wall has passed the stop member.

This action is made possible by constructing 15 the rear end of the drawer to incline rearward, whereby the upper part of the rear end of the drawer is made to extend farther rearward than the lower part of the drawer is extended. The upper part of 20 the rear end of the drawer is still in engagement with the stop member while the lower part of said rear end is free to move outward. Furthermore, this form of the drawer and the positioning of the front edges of the 25 horizontal compartment walls adapt the drawer to make such engagement independently of said stop member as will sustain the drawer when it has been pulled forward far enough to expose the rear part of the 30 drawer to view. The rear end of the bottom of the drawer can rest on the next lower horizontal partition (the partition serving as a fulcrum) while the rearward-extending upper part of the drawer engages the next 35 upper horizontal partition, the latter being set backward far enough to permit looking into and to afford access to the rear part of the drawer. By the use of the structure forming compartments for the drawers as 40 above described, all the drawers may be identical in size and form and freely interchangeable.

Every container, C, is to be filled with a sample lot of candy which the customer can 45 see through the glass, C⁶, in the window opening, C⁶. But said candy is not acces-

sible to the customer. Furthermore, said candy is protected from dust and dirt.

Within the drawer back of the outer wall is to be any desired quantity of the same 50 kind of candy as is shown in the container, C. From such candy in the drawer the customer may be given or allowed to take any desired quantity. Within convenient dimensions, enough drawers may be provided 55 to display a large assortment of candies, one variety being placed in every container, C. Obviously, the size of the structure and the number of drawers it contains may be varied.

60 The drawings show the structure supported on a table, D. Any similar support may be used.

I claim as my invention,

1. In a structure of the nature described, 65 a drawer having a front wall, a container fitted for frictional engagement in the front face of said front wall and the container having a window in its front wall.

2. In a structure of the nature described, 70 a drawer having a fixed front wall in the outer face of which is a chamber, a container fitted into said chamber and comprising a body and a lid one of which has a window.

3. In a structure of the nature described, 75 a drawer having a front wall in the outer face of which is a chamber, a removable container fitted into said chamber, said container having a lid having free side wings adapted to bear against the faces of the 80 chamber.

4. In a structure of the nature described, 85 a drawer having an outer end wall, said wall having a chamber in its outer face, a container having a window in its front and having yielding members adapted to make frictional engagement with the faces of said chamber.

In testimony whereof I have signed my name this 4th day of March, in the year one 90 thousand nine hundred and nineteen.

BURTON L. JOHNSON.
